SHOE RACK

Ira J. Kuert, Los Angeles, Calif.

Application December 27, 1932

Serial No. 648,941

7 Claims. (Cl. 211—37)

This invention relates to improvements in shoe racks.

The general object of the invention is to provide a shoe rack of novel knock down construction.

Another object of the invention is to provide a shoe rack including novel means whereby a number of the racks may be suspended one from the other.

10 Other objects and the advantages of the invention will be apparent from the following description taken in connection with the accompanying drawing wherein:

Fig. 1 is a front elevation showing a plurality of my improved shoe racks operatively connected together.

Fig. 2 is a fragmentary enlarged section taken on line 2—2 of Fig. 1.

Fig. 3 is a fragmentary enlarged section taken 20 on line 3—3 of Fig. 1 and

Fig. 4 is an enlarged transverse section through one of the cross bars.

25 Referring to the drawing by reference characters, I have indicated my improved shoe rack generally at 10. As shown the shoe rack 10 comprises a pair of spaced end members 12 which are connected by three cross shoe supporting bars 14.

30 The end members 12 are preferably made of sheet metal and each includes a side portion 15 and an inturned back flange 16 having an aperture 17 therein adjacent its upper end.

35 Intermediate the width of the side portion 15 and spaced from the top thereof, I provide a clip member 18 and spaced from the bottom of the side portion and positioned adjacent the front and the back thereof I provide similar clip members 19 and 20.

40 Each of the clip members 18, 19 and 20 includes a pair of spaced outstruck fingers having roots 21 at right angles to the portion 15 with the roots continued to form flanges 22 which extend at right angles to the roots and towards each other. The fingers 21 and their associated flanges converge toward each other.

45 Intermediate the width of the side portion 15 and positioned between the upper end thereof and the clip 18 I provide a clip member 23 and adjacent the lower end of the side portion I provide a similar clip 24 positioned between the end of the side portion and the lower ends of the clips 19 and 20. Above and in line with the clip 24 I provide a similar companion clip member 24'.

55 The clips 23, 24 and 24' are similar to the

clips 18, 19 and 20 and each includes a pair of spaced outstruck fingers 24" comprising roots 25 and flanges 26 bent towards each other.

The fingers 24" and their associated flanges of the upper clip member 23 converge towards each other at their upper ends while the fingers 24" and their associated flanges of the lower clip members 24 and 24' converge towards each other at their lower ends.

60 The cross bars 14 are also preferably made of sheet metal and are angle shaped and each includes a top portion 27 and a right angularly bent longitudinal side portion 28. At each end of each bar I provide finger portion 29 which is bent at right angles to the top portion in the same direction as the side portion. The sides of the finger 29 converge towards each other towards the end thereof opposite the top portion of the bar.

65 When the shoe rack 10 is operatively assembled a cross bar 14 is connected to a pair of side members 12 by the clip members 18, 19 and 20 of each of the side members. When a cross bar 14 is operatively connected to a side member by one of its clips the finger portion 29 of the cross bar is positioned between the finger portions 21 of the associated clip and between the face of the side member and the inner faces of the flanges 22.

70 In use the shoe rack 10 is preferably secured to a suitable support 30 by a pair of screws 31 which are positioned in the apertures 17 in the back flanges 16 of the end members 12.

75 For suspending one shoe rack 10 from another I provide a connecting link 32. Each connecting link 32 is preferably made of sheet metal and includes a shank portion 33 having enlarged head portions 34 at opposite ends. The sides of the head portions 34 converge from their outer ends 80 to their juncture with the sides of the shank portion 33.

85 To suspend one shoe rack from the other one end of a connecting link 32 is attached to either the clip member 24 or the clip member 24' of 90 each of the end members of the upper shoe rack and the opposite ends of the links 32 are attached to the clip members 23 of the end members of the lower shoe rack.

95 To operatively attach a connecting link 32 to an associated clip member the head portion 34 of the link is positioned between the face of the side member and the inner faces of the flanges 26 of the clip member with the tapered sides of the head portion of the link engaging the inner 100 105 110

surface of the angularly arranged finger portions 25 of the clip.

Thus it will be apparent that after securing one shoe rack to a support as many other shoe racks as desired may be suspended therefrom by means of the connecting links 32 and it is not necessary to secure each of the suspended racks to the support.

Furthermore the distance between adjacent 10 shoe racks may be varied according to whether the link members are connected to the clip members 24 or the clip members 24'.

It will be noted that the ends of the top portions 27 and the ends of the side portions 28 of 15 the bars 14 directly engage the inner faces of the end members 12 and this in conjunction with the inter-engaging clip members 18 and the fingers 19 produce a firm rigid interlocked effect.

From the foregoing description it will be apparent 20 that I have provided a novel shoe rack which is simple in construction and highly efficient in use.

Having thus described my invention, I claim:

1. In a shoe rack, a pair of side members, a 25 plurality of cross bar members connecting said side members, each of said side members including a pair of clip members, said clip members being positioned one adjacent each end of said side members, each of said clip members including 30 spaced outstruck finger portions arranged parallel to and spaced from the face of said side members, said finger portions of said clip members converging, a pair of link members, each of said link members including a shank portion having an enlarged head portion at each end, the 35 sides of said head portions being tapered outwardly from the sides of said shank portions, the head portions at one end of said link members being positioned between the faces of said side members and the inner faces of said finger portions and with their tapered sides engaging the 40 bases of said finger portions of said clip members.

2. In a shoe rack, a pair of side members, a 45 plurality of cross bar members connecting said side members, each of said side members including a pair of clip members, said clip members being positioned one adjacent each end of said side members, each of said clip members including 50 spaced outstruck finger portions arranged parallel to and spaced from the face of said side members, said finger portions of said clip members converging, a pair of link members, each of said link members including a shank portion having an enlarged head portion at opposite ends, the 55 sides of said head portions being tapered, said head portions at one end of said link members being positioned between the faces of said side members and the inner faces of said finger portions and with their tapered sides engaging the bases of said finger portions of said clip members and a second pair of side members secured 60 to the other end of said link members.

3. In a shoe rack, a pair of spaced side members, a plurality of bars connecting said side members, each of said side members including a 65 plurality of pairs of clip members, each of said clip members including spaced outstruck finger portions having roots arranged at right angles to the face of said side members and having flange portions arranged at right angles to the roots and spaced from the face of said side members, said finger portions of each pair of said clip members converging, each of said bars including 70 a top portion and a longitudinal side portion, a

finger portion at each end of said bar, said finger portion being arranged at right angles to said top portions of said bar, the sides of each of said bar finger portion converging, said bar fingers being positioned between the faces of said side members and the inner faces of said clip flanges with the tapered sides of said bar fingers engaging the inner faces of said clip finger portions.

4. In a shoe rack, a pair of spaced side members, a plurality of bars connecting said side members, each of said side members including a plurality of pairs of clip members, each of said clip members including spaced outstruck finger portions arranged parallel to the side members and spaced from the face of said side members, said finger portions of each pair of said clip members converging, each of said bars including a top portion and a longitudinal side portion, a finger portion at each end of said bar, said finger portion being arranged at right angles to said top portion of each bar, the sides of each of said bar finger portions converging, said bar fingers being positioned between the faces of said side members and the inner faces of said clip flanges with the tapered sides of said bar fingers engaging the inner faces of said clip finger portions, the ends of the top portion of the bar and the ends of the side portion of the bar directly engaging the face of the side members.

5. In a shoe rack, a pair of spaced side members, a plurality of bars connecting said side members, each of said side members including a plurality of pairs of clip members, each of said clip members including spaced outstruck finger portions arranged parallel to the side members and spaced from the face of said side members, said finger portions of each pair of said clip members converging towards one end of said side members, each of said bars including a top portion and a longitudinal side portion arranged at right angles thereto, a finger portion at each end of said bar, said finger portion being arranged at right angles to said top portion of said bars, the sides of each of said bar finger portions converging towards the end opposite said top portion, said bar fingers being positioned between the faces of said side members and the inner faces of said clip flanges with the tapered sides of said bar fingers engaging the inner faces of said clip finger portions, the ends of the top portion of the bar and the ends of the side portion of the bar directly engaging the face of the side members, each of said side members including a flange portion arranged at right angles thereto and each of said side member flanges having an aperture therein adjacent one end thereof.

6. In a shoe rack, a pair of side members, a plurality of bars connecting said side members, each of said side members including a plurality of pairs of clip members, each of said clip members including finger portions spaced from the face of said side member, said finger portions of each pair of said clip members converging, each of said bars including a top portion and a longitudinal side portion, a finger portion at each end of each bar, said finger portion being arranged at right angles to said top portion of said bar, the sides of each of said bar finger portions converging, said fingers of said bars being positioned between the faces of said side members and said clip members, each of said side members including a pair of other clip members, said other clip members being positioned one adjacent each end of said side members, each of said other clip members including spaced outstruck finger por-

tions, arranged at right angles to the face of said side member and including facing flange portions arranged at right angles thereto and spaced from the face of said side member, said 5 finger portions of said other clip members converging, a pair of link members, each of said link members including a shank portion having an enlarged head portion at one end, the sides of said head portions being tapered outwardly, said 10 head portions at one end of said links being positioned between the faces of said side members and the inner faces of said flange portions of said other clip members and with their tapered sides engaging the inner faces of said finger portions of said other clip members.

7. In a shoe rack, a pair of end members, a plu- 20

rality of cross bar members connecting said end members, each of said end members having a pair of clip members, said clip members being spaced apart, each of said clip members including a pair of spaced outstruck finger portions arranged parallel to and spaced from the face of said side members, said finger portions of said clip members converging, each of said cross bar members having a finger portion at each end, the cross bar finger portions being tapered, said cross bar finger portions being positioned between the faces of said end members and the inner faces of said end member finger portions and with the tapered sides of the cross bar fingers engaging the bases 25 of the end finger portions.
